UNITED STATES PATENT OFFICE.

JOHN E. WHITTLESEY, OF PITTSBURGH, PENNSYLVANIA.

SUPERHEATER-BOILER.

1,102,836.

Specification of Letters Patent. Patented July 7, 1914.

Application filed March 11, 1912. Serial No. 683,136.

To all whom it may concern:

Be it known that I, JOHN E. WHITTLESEY, a resident of Pittsburgh, in the county of Allegheny and State of Pennsylvania, have 5 invented a new and useful Improvement in Superheater-Boilers, of which the following is a full, clear, and exact description, reference being had to the accompanying drawings, forming part of this specification, in 10 which—

Figure 1 is a longitudinal vertical section showing one form of boiler embodying my invention. Fig. 2 is a detail sectional view showing the bank of superheater tubes and the headers therefor. Fig. 3 is a cross-section on the line III—III of Fig. 1. Fig. 4 is a view similar to Fig. 2, but showing a modification. Fig. 5 is a view similar to Fig. 1, but showing another modification. Fig. 6 20 is a detail view showing an end elevation of a portion of the superheater tubes of Fig. 5.

My invention has relation to superheater boilers; and is designed to provide a boiler of this type which is free from steam and water drums, and in which the superheating 25 is effected in an upper bank of tubes which are in the last pass of the gases from the grate to the stack.

A further object of my invention is to provide 30 novel baffling means whereby all the steam, before being taken off for use is compelled to pass through all the superheater tubes.

The nature of my invention will be best 35 understood by reference to the accompanying drawings, which will now be described, it being premised, however, that the invention is susceptible of various other embodiments within the scope of my invention, as 40 defined in the appended claims.

Referring first to that form of invention as shown in Figs. 1, 2 and 3, the numeral 2 designates the setting of the boiler, 3 the grate and 4 the bridge wall. 5 designates a 45 lower bank of longitudinally extending downwardly and rearwardly inclined water tubes; 6 a second bank of similar water tubes placed above the first bank; and 7 an upper bank of superheater tubes, the latter being 50 preferably, although not necessarily, of larger diameter than the water tubes. 8 designates a baffling at the bottom of the lower bank of tubes 5, this baffling extending over the grate and also over the bridge 4, 55 so as to cause the gases and products of combustion to pass to the rear end of the fur-

nace and thence upwardly and forwardly underneath a baffling 9, which extends a part of the length of the boiler from the rear end thereof. 10 is another baffling which extends rearwardly from the front end of the boiler. By means of these three bafflings, the products of combustion, when they come in contact with the tubes, are first given a forward pass, then a rearward pass, and 60 then another forward pass to the stack 11. The three banks of tubes, all open into the common headers 12. In order that the steam may be compelled to pass through all of the rows of superheating tubes 7, I provide the 70 rear header 12 with an internal transverse horizontal baffle 13, which compels the steam to pass forwardly into the front header 12; and I provide the latter with the transverse horizontal baffling 14, which compels the 75 steam to be charged into this header to make a rearward pass through the superheater tubes to the rear-header 12 and thus forwardly to the upper row of tubes into the front header above the baffle 14. 15 designates a steam off-take connected to the upper portion of the front header 12. The intermediate bank of tubes 6 add sufficient water tube area to the boiler to take the 80 place of the water area in the usual steam and water drum, while the superheater tubes 7 are preferably equal at least in area to the steam space of the usual drum. I do not, however, limit myself to the use of any 85 particular number of tubes in any of the banks, since these may be largely varied. It will be seen that the superheater tubes 7 are almost entirely above the upper baffle of the boiler, as shown in dotted lines in 90 Fig. 1, and that they provide large superheating area which is directly exposed to the gases in the last pass on their way to the stack. By carrying the superheater tubes 95 in the same headers as the water tubes, I make a very cheap and compact construction and simplify the setting.

In the modification shown in Fig. 4, instead of taking the superheated steam for use from the front header, I take it from the rear header. In this figure the front header 100 is marked 12^a and the rear header 12^b. This arrangement involves a reversal in the relative positions of the baffles which are here indicated at 13^a and 13^b. These two baffles 105 are so arranged as to cause the steam to make its last pass from the upper row of superheated tubes into the upper portion 12^b

from which it is removed by the pipe connection 15^a.

In the modification shown in Figs. 5 and 6, instead of extending all of the superheater tubes 7^a the full length of the furnace, I provide an offset 16 in the roof of the furnace at the front end thereof and in this offset I place U-shaped superheater pipes 7^b, which may be arranged as shown in Fig. 6. These pipes are carried in the front header 12^c, which is provided with a baffle 13^c, so as to cause all the steam to make a last forward pass through the upper legs of the U-shaped pipe 7^b.

The advantages of my invention will be apparent to those skilled in the art, since it provides a compact and cheap form of superheater boiler, in which the superheating pipes can be carried by the same headers as the water pipes, thereby greatly simplifying the construction and setting of the boiler.

It will be noted that in all the forms shown, all the tubes in each horizontal row of superheater tubes open into a common chamber in one or both of the headers. These chambers are of sufficient capacity to act as equalizing chambers, and prevent steam from being drawn unequally from the different tubes, and thus prevent saturated steam from being drawn directly through any tube or tubes into the off-take connection 15. My invention also obviates the use of steam and water drums and provides ample superheating area in the last pass of the gases.

I do not limit myself to the particular embodiments of my invention, which I have herein shown and described, since it is obvious that various changes may be made in the arrangement of the water and superheater tubes, and in the construction and arrangement of the baffling, without departing from the invention as set forth in the appended claims.

I claim:

1. A drumless superheater boiler having a plurality of banks of water tubes arranged one above another in successive

passes of the gases, a bank of superheating tubes arranged above the water tubes and in the last pass of the gases, together with two headers in which the ends of the superheater tubes are secured, said headers forming equalizing chambers for the steam from the superheater tubes, and a single off-take connection leading from one of said headers; substantially as described.

2. A drumless superheater boiler having a plurality of banks of water tubes arranged one above another in successive longitudinal passes of the gases, a bank of superheating tubes arranged above the water tubes in the last pass of the gases, a box header at each end of the boiler, all of said water tubes opening into and connecting the two headers, the superheating tubes all being connected to at least one of said headers, a partition in said last mentioned header, there being an equalizing chamber formed in said header above said partition, and a single off-take connection leading from one of said equalizing chambers; substantially as described.

3. A drumless superheater boiler having a plurality of banks of water tubes arranged one above another in successive longitudinal passes of the gases, a bank of superheating tubes arranged above the water tubes in the last pass of the gases, a box header at each end of the boiler, all of said water and superheater tubes opening at their ends into the said headers, the headers having baffling between the successive rows of superheater tubes whereby the steam is compelled to pass in parallel through the tubes of each horizontal row but in series with successive rows, the last rows of tubes opening into an equalizing chamber in one of the headers, and a delivery pipe leading from said equalizing chamber; substantially as described.

In testimony whereof, I have hereunto set my hand.

JOHN E. WHITTLESEY.
